Primary Examiner — Garth Rademaker*Assistant Examiner* — Laura H Yu(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;
 FIG. 2 is a side view thereof;

FIG. 3 is a rear perspective view thereof;

FIG. 4 is a front perspective view of a shoe showing my new design in an alternate embodiment;

FIG. 5 is a side view thereof; and,

FIG. 6 is a rear perspective view thereof.

In FIGS. 4–6, the broken lines showing the unshaded small circular elements form no part of the claimed design. In FIGS. 1–6, the broken lines depicting the remainder of the shoe form no part of the claimed design.
